UNITED STATES PATENT OFFICE

2,493,303

OPERA CHAIR

Russell H. McCullough, Los Angeles, Calif.

Application November 13, 1945, Serial No. 628,050

8 Claims. (Cl. 155—1)

1

This invention relates to opera chairs and contemplates more specifically individual seats of the type adapted for assembly in rows for use in theatres and the like.

In motion picture theatres it is common practice to provide both loge and general admission seats which differ in their location in the theatre, their size, and in the general comfort afforded. In order to provide greater comfort in the larger loge seats, the latter are more completely enclosed and more heavily upholstered. Moreover, as they are ordinarily arranged at the back of the theatre, they are located at a higher elevation in the building than those available at the lower price of admission. Consequently, such seats are more difficult to properly ventilate. It is economically impractical to construct a single air conditioning unit for such theatre buildings which, without producing an excessive draft of air in the forward or lower areas of the theatre auditorium, where the smaller and more open seats are disposed, will adequately circulate air through the loge section. Accordingly, it often occurs, especially in warm weather, that such seats are actually less comfortable than those available at the lower price of admission.

It is a principal object of the present invention to provide an opera chair intended particularly for use in motion picture theatres but incorporating novel structural features adapted for utility in hospital chairs, automobile seats, and the like, embodying, in an economical construction, numerous features contributing to the greater comfort of the occupant and which in particular incorporates an auxiliary air circulating system whereby air may be released under pressure around an occupant of the chair from both the seat and back in variable volume.

Another object of the invention is the provision of a chair having a pivoted back in combination with a sliding seat, the back and seat being hinged together and adjustable by the occupant with facility, whereby the chair will offer comfortable support to the occupant seated in a substantially upright position or semi-reclining position.

More specifically, it is an object of the invention to provide a plurality of chairs arranged in rows, each equipped with a rolled-upholstered back and seat into which air under pressure may be introduced from a conduit adapted to supply each of the chairs of the row, the air being ejected from orifices between the rolls of the upholstery against and around the occupant therein.

Still another object is the provision in a chair,

of the character last above alluded to, of individual valvular mechanism associated with each chair whereby the occupant may vary the volume of air directed thereto without materially affecting the velocity or quantity of air ejected from the discharge orifices of the other chairs of the group thereof supplied from the same source.

Still another object is to provide a sectional cushion for both seat and back of the chair, each cushion section being individually removable with facility to permit substitution by another when damaged.

Numerous other objects and salient features of my invention, such for example as simplicity of construction, complete efficacy and control of the air circulating system throughout the range of adjustment of the seat and back, adaptability to variations in design and arrangement as well as in the style of upholstery utilized, economy of manufacture and relatively small size of the individual chairs, will be apparent to those of skill in the art upon an examination of the following description read in the light of the accompanying drawings in which:

Fig. 1 is a front perspective view, partially broken away, of a chair embodying my invention;

Fig. 2 is a perspective view taken from the back of one of the seats showing the foot rest for the occupant of the seat directly to the rear of the one shown;

Fig. 3 is an enlarged vertical section, partially broken away, through the end chair of a row of chairs depicting the fan for circulating air through all of the chairs in the row;

Fig. 4 is a transverse vertical sectional view through the seat structure of the chair, showing the rollers on which the seat is movable;

Fig. 5 is a fragmentary horizontal section, illustrating the arrangement of the seat supporting elements;

Fig. 6 is a perspective view of the back and seat and single cushion depicting one embodiment of the means for releasably securing the cushion sections in place;

Fig. 7 is a fragmentary sectional view of the back and arm of the chair, showing in elevation one of the pins by which the back is variably supported.

Referring to the drawings in detail, the numerals of which indicate similar parts throughout the several views, 10 designates generally the supporting frame of each of a plurality of chairs arranged in rows as indicated in Fig. 1. Supporting frame 10 for each chair comprises a pair of vertically-disposed side standards 11, one

being located between each pair of chairs and common to both to afford support for each thereof. An additional standard 11 is disposed at each end of the row to assist in supporting the end chairs. The particular form of side standards 11 may vary widely in specific embodiments, but is preferably of sufficient width to assure firm support and to separate the seats (later described) of adjoining chairs, and of a height to provide a mounting for a conveniently located arm rest 13.

A pair of channels 14 are secured in horizontal position by suitable means to opposing surfaces, respectively, of the pair of standards 11 of each chair for the slidable support of a box-like seat frame 15. The top 16 of seat frame 15 is of a width to closely approximate the distance between channels 14. A series of rods 18 extend transversely under the seat frame 15 and project into slots 19 in the channels 14. Rollers 20, journaled on the ends of rods 18, are housed within channels 14 and bear upon the bottom of the channels, respectively, to support the seat 15 as well as the back of the chair, about to be described.

The back of each chair comprises a box frame 21 of a width conforming with that of seat 15, but is preferably of greater length. The lower edge of the forward wall 22 of the frame is pivotally connected by one or more hinges indicated generally at 23 to the rearward end of the top 16 of seat frame 15, whereby the angle between the back 21 and seat 15 may be varied in accordance with the comfort requirements of the occupant. The back 21 is supported in any adjusted tilted relationship by pins 24 which are mounted in the rearward ends of arms 13 and project into slots 25 in sides 26 of back frame 21, so as to maintain the adjusted angle of the back while permitting the lower end of the back to follow the seat forwardly when this adjustment is desired and increase its angle of inclination in accordance with the desired adjustment effected by the occupant. A strip 27 of fabric, leather or other flexible material is connected across the breach between the rear wall 28 and sides 26 of the back frame 21 and the bottom 29 and sides 17 of the seat frame 15 to complete the enclosure of the composite frame without interfering with the pivotal relationship between the back and seat. It will be observed that the lower end of the back frame 21 and the rearward end of the seat frame 15 are open, whereby the interiors of the two frames 15 and 21 are in unrestricted communication with one another for a purpose hereinafter more fully described.

The upholstery may be of any type well known in the art but preferably comprises a plurality of elongated blocks 30 of sponge rubber, each structurally separate from one another and individually removably secured to the back and seat frames. Each block 30 is flat on one side which normally bears against the back or seat frame to which it is attached, and its outer surface is arcuate to form with the other blocks 30 a composite billowed cushion-surface. The underside of each block 30 is provided with a pair of staples 52 arranged in spaced relation and adapted to engage, respectively, a complementary pair of transversely-aligned hooks 53, pairs of which are appropriately arranged on the back and seat. The free ends of hooks 53, mounted on the back frame 21, are directed upwardly whereby the respective cushion blocks 30 to be associated with the back are engaged in operative position by

their downward movement after first aligning staples 52 with the hooks by which respective blocks 30 are to be retained in place. Hooks 53 on the seat frame 15 are directed laterally so as to engage staples 52 of the seat cushion blocks in response to movement of the blocks longitudinally, the staples 52 on the seat cushion blocks 30 being rotated 90° with respect to those adapted for attachment to the back.

Air is circulated beneath the seats of each row thereof through a sectional conduit 31, the air being drawn into the conduit at one end of the row of chairs and diverted into the seat frame 15 for expulsion through orifices 32 in the seats and backs of the chairs, respectively, in a manner about to be described, or from the opposite end of conduit 31. Each pair of standards 11 is accordingly formed with aligned openings into registry with which the ends, respectively, of a section 33 of conduit 31 are secured by suitable means. Each section 33 is in open communication with the like-numbered section carried below the adjoining seat, and is sealed against the release of any of the air circulated under light pressure therethrough. The openings in the supporting standards 11 at the end of each row in which the conduit sections 33, under the end chairs, are secured, are covered with circular plates 34 having a plurality of downwardly-directed louvers 35 therein. An electric motor 36 is supported coaxially in conduit 31 adjacent one of the louvered plates 34 by a web 37. The motor shaft 38 carries a fan 39 effective to draw air through the louvers and induce a draft of air through the conduit.

The air flow through conduit 31 is tapped beneath each chair by a tube 41 which projects through and is secured rigidly in a hole in the upper arc of the conduit intermediate the side standards 11. The open end 42 of each tube 41 is bent within the conduit to extend toward the direction from which the air flows and the outer end extends laterally of conduit 31 directly below the seat frame 15 and in a direction parallel to that in which the latter is movable on the rollers 20. A second tube 43, one end of which is telescopically associated with tube 41, is mounted to the undersurface of the bottom 29 of seat frame 15 by suitable means so as to move therewith, the opposite end of tube 43 being turned upwardly to project through the bottom 29 of the seat frame 15 and into the interior thereof. Air thus diverted from the conduit into the seat and back frames 15 and 21 through the tubes 41 and 43 is released through a plurality of orifices 32 arranged in rows in the top 16 of the seat frame 15 and in the forward wall 22 of the back frame 21, the respective rows of orifices 32 being disposed between pairs of sponge rubber cushion blocks 30.

The volume of air diverted from the conduit into each chair may be controlled manually by the occupant thereof. To this end valvular mechanism for each tube assembly is provided comprising a baffle 44 pivotally connected to the lower arc of the end of tube 41 within conduit 31. The manually-actuated control for regulating the position of baffle 44 comprises a Bowden wire 47 which is connected to baffle 44 at a point diametrically opposed to its hinged connection with the tube 41. Wire 47 extends through a flexible conduit 48, the wire and conduit 48 projecting through the wall of conduit 31 and thence laterally to one of standards 11 and then upwardly to

a point below the adjacent arm 13. Wire 47 projects from the end of the flexible conduit for attachment through a link 49 to an actuating lever 50 pivoted to standard 11 as at 51. It will be observed that by pushing lever 50 in a forward direction, tension is applied to wire 47, and the normally-open baffle 44 is drawn toward its closed position. Movement of lever 50 rearwardly is in a like manner transmitted to baffle 44 so as to compel the latter to open to an extent corresponding to the degree of movement of the lever.

It will thus be seen that I have provided an opera chair of a type adapted for assembly in rows for use particularly in motion picture theatres and the like, each chair incorporating novel features contributing to greater comfort incident to the embodiment of an adjustable seat and back to support the occupant variably from an upright sitting position to a semi-reclining position, adjustment of each chair in this respect being effected by the occupant incident to shifting his weight upon or pressure against different elements of the chair, as will be obvious, and further of an air circulating system whereby air is ejected through or between the cushions of both back and seat to cool and ventilate the immediate area in which the occupant of the chair is accommodated the velocity and volume of air emitted being subject to positive manual regulation with facility.

While I have shown and described but one embodiment of my invention, it will be apparent to those of skill in the art to which my invention relates that numerous changes in size, design, shape and number of the parts may be made, that any conventional valvular mechanism may be substituted for baffle 44 by which the volume of air diverted from conduit 31 into the chair is regulated, and correspondingly a different mechanical or electrical control may be employed for such valve, that several rows of chairs may be supplied with air from a single fan or an external source, and the velocity of the air flow produced by the fan 39 may be variably controlled by incorporation of conventional means with which the art is familiar, all without departing from the spirit of my invention as defined in the appended claims.

What I claim and desire to secure by Letters Patent is:

1. In a chair, a seat comprising a base frame and a plurality of separate cushions, means securing each of said cushions to said base frame forming air passages therebetween, and means carried by said base frame to eject air from said seat between said cushions through said respective air passages.

2. In a chair, a pair of standards, a seat frame, means to slidably support said seat frame between said standards, a cushion supported on said seat having air passages therethrough, a conduit below said seat, means to produce a flow of air in said conduit, and means to divert a part of the flow of air in said conduit through said air passages throughout the range of movement of said seat.

3. In a chair, a pair of standards, a seat frame, means to slidably support said seat frame between said standards, a cushion supported on said seat having air passages therethrough, a conduit below said seat, means to produce a flow of air in said conduit, means to divert a part of the flow of air in said conduit through said air passages throughout the range of movement of

said seat, and valve means to vary the quantity of air directed through said air passages.

4. In a chair, a pair of standards, a seat frame, means to slidably support said seat frame between said standards, a cushion supported on said seat having air passages therethrough, a conduit below said seat, means to produce a flow of air in said conduit, means to divert a part of the flow of air in said conduit through said air passages throughout the range of movement of said seat, valve means to vary the quantity of air directed through said air passages, and a manual control associated with one of said standards to control said last-named valve means.

5. In a chair, a pair of standards, a hollow seat frame and a hollow back frame, means to support said frame for movement between said standards and relative to one another, each of said frames having an air chamber therein, means to flexibly connect said frames to one another, flexible means to communicate said chambers with one another, a plurality of cushions, means to separately attach said cushions to said frames, respectively, in spaced relation, said frames having vent openings therein between said cushions, and means to supply air under pressure to said chambers for expulsion through said vent openings between said cushions throughout the range of movement of said seat and back frames.

6. In a chair, a pair of standards, a hollow seat frame and a hollow back frame supported between said standards, each of said frames forming an air chamber therein, a plurality of cushions, means to attach each of said cushions independently of one another to said frames, respectively, in spaced relation to form air passages therebetween, said frame having vent openings therein disposed in alignment and communicating with said air passages between said cushions, respectively, and means to supply air under pressure to said chambers for expulsion through said vent openings and air passages and between said cushions.

45 7. In a chair, a pair of standards, a hollow seat frame and a hollow back frame supported between said standards, each of said frames forming an air chamber therein, means to communicate said chambers with one another, a plurality of cushions, means to attach each of said cushions independently of one another to said frames, respectively, in spaced relation to form air passages therebetween, said frame having vent openings therein disposed in alignment and communicating with said air passages between said cushions, respectively, and means to supply air under pressure to said chambers for expulsion through said vent openings and air passages and between said cushions.

60 8. In a chair, a pair of standards, a hollow frame forming an air chamber therein, a pair of cushions, means to attach said cushions to said frame in spaced relation to form an air passage therebetween, said frame having a plurality of vent openings therein in alignment and communicating with said air passage to communicate the interior of said frame with said air passage, and means to supply air under pressure to said frame for expulsion through said vent openings and thence through said air passage.

RUSSELL H. McCULLOUGH.
